The ornamental design for an automated periodontal probe handpiece, as shown and described.

DESCRIPTION

FIG. 1 is a top view of the automated periodontal probe handpiece, showing our new design;

FIG. 2 is a top view of the automated periodontal probe handpiece, showing the disposable probing portion removed from a receiver portion of the handpiece;

FIG. 3 is a bottom view of the handpiece of FIG. 1;

FIG. 4 is a bottom side view of FIG. 2;

FIG. 5 is a side view of the handpiece of FIG. 1;

FIG. 6 is a side view of the handpiece of FIG. 2;

FIG. 7 is a front view of the handpiece of FIG. 5;

FIG. 8 is a rear view of the handpiece of FIG. 5;

FIG. 9 is a rear view of the disposable probing portion of FIG. 6; and,

FIG. 10 is a front view of the receiver portion of the handpiece of FIG. 6.

The broken line showing of the cord in FIGS. 1-6 is for illustrative purposes only and forms no part of the claimed design.
